C. E. FULLER

SMOKE HOOD

Original Filed August 1, 1925

Patented July 27, 1926.

1,594,166

UNITED STATES PATENT OFFICE.

CLAUD E. FULLER, OF NEW YORK, N. Y.

SMOKE HOOD.

Application filed August 1, 1925, Serial No. 47,489. Renewed June 22, 1926.

My present invention relates to brick machinery, and more particularly to an improved apparatus for facilitating the burning of brick.

In the patent granted to Julius H. Bach, 1,071,014, dated August 26, 1913, there is described and claimed an improved apparatus for facilitating the burning of brick consisting of a hood arranged above a kiln and movable over the top of the kiln. Such hood is adapted to collect the smoke and products of combustion as they arise from the burning kiln and to collect and pass such smoke and products of combustion into a collecting flue provided with a plurality of openings adapted to register with the smoke hood in its travel over the top of the kiln. This conduit is connected with the preliminary drying apparatus where the heat units contained in the smoke or products of combustion are utilized to dry the brick in the drier and are then forced up through the stack preferably by a power blower. Such a structure as is shown in the Bach patent, however, lacks the advantage of being portable and therefore readily movable from place to place. My present invention is to be considered an improvement over the structure shown in the patent to Bach and, in carrying out my invention, I have kept in mind the idea of portability, and, further, the necessity for properly and rigidly supporting the outer ends of the smoke hood when the same are used in wide kiln sheds, and also in this latter connection, my invention contemplates the use of apparatus for holding the bracing posts of the kiln and on which posts are arranged one of the tracks—the outer one—on which the hood travels longitudinally of the kiln. By my improved invention it is possible to take care of a relatively large kiln with a relatively few sections or outer supporting devices as, after a portion of the kiln of brick is burned, the hood may be moved forward onto a burning section, the runway supports, etc., that have been vacated in the movement of the hood, being moved forward in preparation for the next forward movement of the hood. This construction has a decided advantage in that, once the runway supports, etc., are moved forward, it gives clear access to the kiln of burnt brick, both for the operation of the brick handling crane, if such is used, and the handling of the brick trucks. By my inven-

tion, therefore, a comparatively small number of posts and beams suffices to handle the burning, whereas if as in former constructions, they were left permanent there would be required enough parts to reach the full length of the kiln. In building a kiln in a wide kiln shed and in connection with the present invention, I preferably employ the portable scoving shown and described in my copending application, Serial No. 65707,856, filed Jan. 21, 1924 which has resulted in Patent 1,548,794, Aug. 4, 1925.

The principal object of my invention, therefore, is an improved smoke hood for brick kilns.

Another object of my invention is an improved apparatus for supporting a relatively narrow smoke hood in a relatively wide kiln.

A further object of my invention is an improved smoke hood runway supporting means.

Other objects and novel features of the construction and arrangement of parts comprising my invention will appear as the description of the invention progresses.

In the accompanying drawing illustrating the preferred embodiment of my invention,

Fig. 1 is an end elevation of a portion of a relatively wide kiln shed showing a relatively narrow smoke hood positioned therein.

Referring to the drawings, 10 designates a base on which is mounted a kiln shed, of which there is shown one such frame member 11, and carrying at its top a longitudinally extending angle bracket 12 to which bracket, and the top of the frame member 11, is secured a transverse supporting bar 13, this bar, as is usual, extending from the side frame member 11, (shown) to the corresponding side frame member of such kiln (not shown). Resting on the end of the cross frame member 13 and extending upward at an angle to the horizontal 95 is the roof beam 14. The lower end of the roof beam 14 is supported from the side frame member 11 by the strut 15. The kiln shed is assumed to have built thereunder and on the base 10 the kiln 16, the material within the kiln being secured in position against lateral bulging by the portable scoving 17, such as is disclosed and claimed in my copending application above referred, this portable scoving being secured in posi-

tion in the usual manner. Obviously, from an inspection of the drawing, the kiln 16 is of considerably less width than the width of the kiln shed. As it is desirable to utilize as much of the products of combustion as may be possible after such products have served their purpose in and during the process of burning of the kiln, there is arranged over the kiln and in close proximity thereto a smoke hood 18, this smoke hood being similar in construction to the smoke hood described and claimed in the patent to Bach, 1,071,014 and above referred to. This smoke hood is provided at what may be termed the outlet end thereof with a downwardly depending member 19 on which is secured a laterally extending stub shaft or shafts 20 and on such shaft or shafts is rotatably mounted a double-flanged wheel or wheels 21. This flanged wheel or wheels run on an I beam or track 22 secured to plate 23 supported on brackets 24 secured to the side frame members 11, but one of which is shown. The end of the smoke hood 18 remote from the downwardly depending plate 19, is closed and has secured thereto a plate 25, this plate at its lower end having secured thereto laterally an extending stub shaft or shafts 26 on which is rotatably mounted a plane pulley roller or rollers 27. This pulley roller or these pulley rollers 27 runs or run on an I beam 28 extending parallel to the I beam 22. In order that the I beam 28 be supported, and as it is not possible to depend on the side frame member or members 11 on the side of the kiln shed (not shown in the drawing), I have provided vertically arranged channel members 29 (but one of which is shown) tied together by longitudinally extending I beams 30, and in the floor or base 10 arranged a plurality of holes or sockets into which the lower ends of the vertically arranged I beams 29 may be set, as clearly shown in the drawing. Secured to the upper ends of some or all of the vertically arranged I beams 29 are vertically arranged I beams 31 of slightly less cross sectional area and to the upper ends of such I beams 31 and on the inner faces thereof are secured eye bolts 32. Adjacent to the exit or inner end of the smoke hood 18 and on the main portion of the side frame members 11 is secured an I beam 33, this I beam being provided, as is usual, with a track 34 on which may run the crane (not shown) located within the kiln shed. Secured to the upper flange of the I beam 33 and at intervals along the length thereof are eye bolts 35, the free ends of which are threaded to form part of a turnbuckle 36, the other portion of this turnbuckle comprising a threaded eye bolt 37. Between the eye bolt 37 of the turnbuckle 36 and the eye bolt 32 on the

upper inner face of the I beam 31 extends a rod 38. When the I beams 29 are placed in position, the turnbuckles 36 are operated to bring the upper ends of the I beams 29 into the position shown with the longitudinally extending I beam 28 in position to be engaged by the pulley roller or rollers 27.

Secured to the side frame members 11 and spaced along the length of the kiln 75 shed are conduits 39 which connect successively with the exit end of the hood 18 as the same is moved along the top of the kiln 16. These conduits 39 connect with a collecting conduit 40 mounted on bracket members 41 secured to the side frame members 11 and from which conduit the products of combustion are carried to a drying apparatus (not shown) and from thence to a stack.

The length of the longitudinally extending I beams 30 may be made as short or long as desired, but preferably short enough so that the required number of vertical supports 29 may be few enough in number to provide for the easy handling of the unit composed of the members 28, 29, 30 and 31. Several of these units will be required, but the combined length thereof falls far short of the entire length of the kiln shed. Therefore, assuming that we have three sections or units and that the burning of the kiln is started at one end of the kiln shed, as soon as one portion of the kiln is burned, the smoke hoods 18 are moved forward on their runways and onto an unburned section. As soon as the smoke hoods 18 have moved off the first unit composed of the members above enumerated, such unit is lifted by the usual crane and moved forward into alignment with the most forwardly arranged section 105 or unit. This moving of the unit from adjacent the burned section of the kiln leaves the entire width of the kiln free so that the usual crane may be readily operated or the trucks usually employed may be readily handled and the burned brick removed at a minimum of cost.

While I have necessarily shown and described the preferred embodiment of my invention somewhat in detail, it is to be understood that I may vary the size, shape, and arrangement of parts within wide limits without departing from the spirit of the invention.

Having thus described my invention, what I claim as new is:

1. An improved track support for supporting the smoke hood track when the same is used in a wide kiln shed, and comprising kiln shed side frame members, a plurality of vertically arranged uprights arranged parallel thereto and spaced apart therefrom, a horizontal track secured to the upper ends of said supports and lying parallel with the side of the kiln shed, and adjustable means

for maintaining the upper end of the supports in alignment with the kiln side frame members.

2. An improved means for supporting a smoke hood in a wide kiln shed and comprising kiln shed side frame members, a supporting track secured thereto and extending longitudinally of the kiln shed, a plurality of vertically arranged supporting standards mounted in sockets in the base of the kiln shed and lying parallel to the kiln shed frame members, a supporting track secured to the top of said supporting standards and lying parallel to the first said track, auxiliary standards secured to the top of the first said standards, and adjustable means secured to the upper ends of said auxiliary standards and having their other ends secured to the kiln side frame members, and

means for adjusting said last said means whereby said second tracks may be maintained rigid with respect to and lying parallel to the first said tracks.

3. An improved track support for supporting a smoke hood track when the same is used in a wide kiln shed and comprising kiln shed side frame members, a plurality of portable vertically arranged uprights arranged parallel thereto and spaced apart therefrom, a horizontal track secured to the upper ends of said supports and lying parallel with the side kiln shed, and adjustable means for maintaining the upper end of the supports in alignment with the kiln side frame members.

In testimony whereof, I have signed my name to this specification.

CLAUD E. FULLER.
